UNITED STATES PATENT OFFICE.

VICTOR A. KIRKEBY, OF SHAKOPEE, MINNESOTA.

COMBINED MATCH BOX AND IGNITER.

1,235,488.

Specification of Letters Patent. Patented July 31, 1917.

Application filed June 28, 1916. Serial No. 106,467.

To all whom it may concern:

Be it known that I, VICTOR A. KIRKEBY, a citizen of the United States, residing at Shakopee, in the county of Scott and State 5 of Minnesota, have invented new and useful Improvements in Combined Match Boxes and Igniters, of which the following is a specification.

This invention relates to pocket match 10 boxes, and more particularly to a combined match box and igniter, which shall be simple in construction, neat in appearance, and so designed to cause the matches contained within the match box to ignite during the 15 extraction of the same from the box.

With the above and other objects in view, the invention consists in the novel features, 20 details of construction and combination of parts which will hereinafter be more fully set forth, illustrated in the accompanying drawing, and pointed out in the appended claim.

Figure 1 is a perspective view of the match box shown in open position;

Fig. 2 represents the form of blank from 25 which the box is made;

Fig. 3 is a perspective view illustrating the box in closed position;

Fig. 4 is a vertical section; and

Fig. 5 is a transverse section.

Fig. 6 is a further view of the blank from 30 which the box is made, clearly illustrating the point of location of one of the igniters thereon.

Referring more particularly to the accompanying drawing, in which like characters of reference refer to corresponding parts in the several views, 5 denotes the blank from 35 which the box is constructed, and preferably consisting of paper, card board or similar substance comprising oppositely disposed sides 6 and 7. The side 6 is provided along its opposite longitudinal edges with opposite laterally extending extension 40 flanges 9, adapted when the blank is in box

flanges 9, adapted when the blank is in assembled form, to be bent inwardly over the opposite edges of the side 7. These flaps, to an extent, will serve as end walls for the match box. In order to bend the

side flaps 9 upon the side 7, I form contiguous with the free transverse edge of the latter, an end flap 10 of a length equaling the length of the respective sides 6 and 7 of the box, and to accomplish this purpose, the 50 said end flap 10 is bent to overlie the side 7 of the box, in order that the same may con-

ceal between the confronting faces of the side 7 and end flap 10, the side flaps 9 of the box. As shown in Fig. 1 of the drawing, the matches 11 when inserted within the box 60 5 protrude above the upper open end of the box; in view thereof, I have formed the closure flap 12 of greater length than the length of the sides 6 and 7 and the end flap 10. This closure flap is bent at the point indicated by the dotted line 13 and adapted when in a closed position, to fold over and upon the exterior surface of the end flap 10 and be retained in closed position through 65 the medium of the tongue 14 being inserted 70 in the slot 14' of the end flap 12.

Arranged transversely upon one of the faces of the side 6 of the box transversely thereof, and disposed transversely on the opposite face of the flap 10, are narrow 75 strips of sand paper 15 and 15' respectively; thus when the box is in assembled form, the strips of sand paper will be arranged in confronting relation one to the other at a point adjacent the top edge of the box, enabling the matches 11 to be ignited upon 80 their extraction or discharge from the match box. It will, of course, be understood that the destructible means 18 serves to hold the box in assembled form, and this destructible means is shown as fastened to the end flap 10 and to the side wall 6 of the box. 85

From the foregoing description, taken in connection with the accompanying drawing, the advantages of construction and of the 90 method of operation will be readily apparent to those skilled in the art to which the invention relates, and while I have described the principles of operation of the invention, together with the device which I now consider to be the best embodiment thereof, I 95 desire to have it understood that the device shown is merely illustrative, and that such changes may be made when desired as are within the scope of the claim appended thereto. 100

I claim:

A match box constructed from a single blank of material bent to provide oppositely disposed sides, extension flaps formed on 105 the longitudinal edges of one of said sides, an end flap formed on the other of said sides and adapted to be folded over and upon the said extension flaps and upon the side with which the end flap is formed, and 110 a closure flap formed on the first mentioned side and of a greater length than the end

flap, permitting the same to be folded over the projecting portions of the contents of the box and upon the first mentioned end flap, a strip of sand paper secured to the upper confronting faces of one of the sides, a second strip of sand paper secured to one of the faces of the end flap and disposed in opposition to the former mentioned strip

when the blank is in assembled form and destructible means for holding the end flap ¹⁰ in closed position.

In testimony whereof I affix my signature.

VICTOR A. KIRKEBY.
